UNITED STATES PATENT OFFICE.

JEROME MAIBAUM, OF NEW YORK, N. Y., ASSIGNOR TO THOMAS E. MURRAY, OF NEW YORK, N. Y.

LOCKING-SWITCH.

1,120,210.

Specification of Letters Patent.

Patented Dec. 8, 1914.

Application filed July 11, 1913. Serial No. 778,430.

To all whom it may concern:

Be it known that I, JEROME MAIBAUM, a citizen of the United States, residing at New York, in the county of New York and State of New York, have invented a certain new and useful Improvement in Locking-Switches, of which the following is a specification.

The invention is a locking switch of the blade or knife type, designed more especially for conditions under which currents of high voltage are to be transmitted—as, for example, from the bus-bar of a generating station to the service leads. Where a pivoted blade switch is thus used, it becomes subjected to enormous stresses due to the tendency of a movable conductor so to move as to include the greatest number of lines of force. The result is that the blade tends to leave its coöperating contact and so open the circuit, while the two supports which respectively carry the blade and contact tend to spread apart and break. There are thus two components of force to be met, namely, one in the direction of the arrow *a* in Fig. 1 of the accompanying drawings, and the other at right angles thereto in the direction of the arrow *b*, both components being in the same plane, which is also the plane of movement of the blade.

My invention is a locking device for the blade, so constructed and arranged as to operate in a direction perpendicular to the aforesaid plane of movement, and thus to prevent both the separation of the blade from its contact and the spreading apart of the blade and contact supports. Furthermore, the magnetic lines of force at the lock are parallel to the direction of motion of the bolt, and hence any current, eddy or otherwise, that it might carry cannot produce a force tending to withdraw said bolt from locked position.

My invention further consists in the construction of the insulating supports for the blade and coöperating contact, and of the lever blade and operating device for the bolt, whereby said blade may be moved into and out of circuit-closing position, without necessitating dangerous proximity of the operator to the switch.

In the accompanying drawings—Figure 1 is a vertical longitudinal section of my locking switch. Fig. 2 is a vertical section on the line *x*, *x* of Fig. 1, showing the lock-

ing bolt engaged. Fig. 3 is a similar section, showing the mode of releasing the lock. Fig. 4 is a top view of the locking end of the switch. Fig. 5 is a vertical section of a modified form of the locking device on the line *y*, *y* of Fig. 6, showing the bolt engaged. Fig. 6 is a similar section, showing the mode of releasing the lock. Fig. 7 is a side elevation and Fig. 8 is a top view of the locking device of Figs. 4 and 5.

Similar numbers and letters of reference indicate like parts.

The switch blade *A* is preferably supported upon two metal rods 1, 2, which are received in bushings 3, which are inclosed in sleeves 4 of insulating material. Each sleeve is made in two shouldered parts 5, 6, one having an annular projection entering an annular recess of the other and receiving between their shoulders the supporting base, preferably also of insulating material. The lower ends of the rods 1, 2 may be threaded to receive nuts 8, by setting up which the sleeves are tightly clamped upon said base. To the rod 2 may be connected a clamping frame 9, which carries the laminated bus-bar 10. Upon the rod 1 is carried the bracket 11, to which is pivoted the switch blade *A*. A main circuit conductor 13 is secured to a projection 14 on said bracket.

The upper end of rod 2 is threaded to receive the metal block *B*, preferably of copper. Said block is vertically recessed to receive the free end of the switch blade *A*, and has an extension *C* carrying spring contacts *D* which bear upon the side of said blade when said blade is in circuit-closing position, as shown in Fig. 1. In said block slides the beveled locking bolt *E*, having an upward projection *F* which travels in a slot *G*, when said bolt is longitudinally moved. Secured to said block is a cup-shaped casing *H*, preferably of manganese bronze, having a central opening in its outer wall, through which passes a guide-rod *I* fast on bolt *E*. There is a collar *J* on said rod, and between said collar and said casing wall is a helical spring *K* which normally tends to move said bolt into locking position, as shown in Fig. 2, the bolt then entering an opening *L* in blade *A* which registers with the bolt in block *B*. Above the opening *L* in lever *A* is another opening *M*, for a purpose to be explained.

When blade A is brought into the recess in block B it meets the beveled end of bolt E, and so forces said bolt rearwardly, compressing spring K until the opening L comes 5 opposite the bolt end. The bolt is then free to be thrown forward by the compressed spring thus entering opening L and locking blade A in closed position.

In order to manipulate the blade A, I provide any suitable handle or rod of wood or other insulating material, having at its end a ferrule having two metal projections N, O. In closing the blade, the short projection N is inserted in opening M, and the 10 blade is then operated. To raise the blade, the longer projection O is inserted in said opening until the edge of the blade enters a groove P on the upper side of said projection, as shown in Fig. 3. The end of projection O then meets the projection F and pushes the same rearwardly until the end of the bolt clears the opening L in blade A, after which said blade may be raised by the 15 rod or handle. An operating rod, such as described, is necessary, because the very high voltage which the switch controls renders it impossible for the operator to use his hands, or even nearly to approach the switch. In 20 practice, I make said rod some seven or eight feet in length.

Referring to the modified form of my device shown in Figs. 5 to 8, inclusive: The bolt E is slotted to receive one end of a bell crank lever Q which is pivoted in lugs R 35 on the block B. The casing H is suitably lengthened to accommodate the longer bolt, and has a slot S in its wall to permit the play of bell crank lever Q. The short projection N enters the opening M in blade A 40 and is used, as before, in moving said blade to closed and locked position, as shown in Fig. 1, dotted lines. When it is desired to raise blade A, the projection O is inserted

into opening M, so that, as shown in Fig. 6, it will push down the upper arm of bell 45 crank lever Q, thus withdrawing the bolt. The blade A is then lifted by the operating rod, as already described.

I claim:

1. A switch, comprising two supports, a 50 lever blade pivoted to one of said supports and coöperating with a circuit terminal on the other support, a bolt slidable in said last-named support in a direction perpendicular to the plane of movement of said 55 blade and entering an opening in said blade, a spring for holding said bolt in engagement with said blade, and a lateral projection on said bolt: the said blade having a second opening registering with said lateral 60 projection when said blade is engaged by said bolt.

2. A switch, comprising two supports, a lever blade pivoted to one of said supports and coöperating with a circuit terminal on 65 the other support, a bolt slidable in said last-named support in a direction perpendicular to the plane of movement of said blade and entering an opening in said blade, a spring for holding said bolt in engagement with 70 said blade, a lateral projection on said bolt, the said blade having a second opening registering with said lateral projection when said blade is engaged by said bolt, and a separate bar constructed to enter said second 75 opening to meet said projection and retract said bolt and having a recess engaging with the edge of said opening when said bolt is retracted.

In testimony whereof I have affixed my 80 signature in presence of two witnesses.

JEROME MAIBAUM.
